UNITED STATES PATENT OFFICE.

AMOS H. DEUSE AND JAMES S. DEUSE, OF CHESTER, CONNECTICUT.

DIE FOR FORMING DOUBLE-TWIST GIMLETS.

SPECIFICATION forming part of Letters Patent No. 224,156, dated February 3, 1880.

Application filed June 20, 1879.

To all whom it may concern:

Be it known that we, AMOS H. DEUSE and JAMES S. DEUSE, of Chester, in the county of Middlesex and State of Connecticut, have invented a new and Improved Die for Making Double-Twist Gimlets, Bits, &c., of which the following is a specification.

Figure 1 is a plan of one half of the die. Fig. 2 is a plan of the other half of the die. Fig. 3 is an elevation of a gimlet or bit made in the same die from a round rod. Fig. 4 is a diagonal section on line *x x*, Fig. 1. Fig. 5 is a diagonal section on line *y y*, Fig. 1.

Similar letters of reference indicate corresponding parts.

This invention relates to that class of dies that are used for forming the double spiral grooves or twists in gimlets, bits, and the like.

The invention consists in the peculiar construction of the die, as hereinafter described.

Referring to the drawings, A A represent the halves of the die, having the longitudinal slightly-tapering grooves *b*', diagonally across which are the bars *c*' *d*', which preferably are cast as part of the block. These two parts of the die are to be set together face to face, as shown in section in Figs. 4 and 5, so that the bars in the one half shall lie across those in the other half, and be firmly held in that position while the heated and malleable gimlet or bit blank, which is a round rod, is entered and turned or twisted into the die until the point is carried beyond the two rear bars, *d*', when the die is opened and the blank withdrawn in the condition shown in Fig. 3.

It will be seen that the bars *c*', which are

nearest to the front of the die, taper on their faces from their inner to their front ends. The advantage of thus shaping the bars is, that they make the grooves where they run up on the shank, as at *e*', shallow, thereby leaving the tool stronger at that point than at any other part of the twist.

The rear bars, *d*', are made larger than the others, so that they may "spread" the grooves and "swell" the tool towards its screw end, making it larger there, so that it may easily bore deep. This shape, which is the reverse of the old-style tool, gives to our tools a great advantage over others, as a deep hole can be bored with them without any "binding" on the shank or parts above the swell *f*'.

The tool-blank is entered into the dies at a bright-red or higher temperature, so that it may become easily shaped.

Having thus described our invention, we claim as new and desire to secure by Letters Patent—

The die for forming double spiral grooves in bits or gimlets, consisting of the two halves A A, having the longitudinal and slightly-tapering grooves *b*' and the diagonal cross-bars *c*' *d*', the bars *c*' being smaller than bars *d*', and tapering on their faces from the inner to the front ends, substantially as shown and described.

AMOS H. DEUSE.
JAMES S. DEUSE.
